UNITED STATES PATENT OFFICE.

LAWRENCE F. BAASH, OF WHITTIER, CALIFORNIA.

WELL-CASING SHOE.

Application filed April 18, 1922. Serial No. 554,727.

To all whom it may concern:

Be it known that I, LAWRENCE F. BAASH, a citizen of the United States, residing at Whittier, in the county of Los Angeles and 5 State of California, have invented new and useful Improvements in Well-Casing Shoes, of which the following is a specification.

This invention relates to well casing shoes and has for its object to provide a well casing shoe of economical cost of construction.

It is common practice in drilling deep wells to lower a casing into the well hole, and the foot end of the casing is provided with a so-called "shoe" for the protection of 15 the lower end of the casing, and this shoe is ordinarily made of high grade steel to withstand the wear and it is generally machined throughout its length on the inside and on the outside. This, obviously, is expensive 20 both in the cost of material of which the shoe is formed, and in the cost of machining.

Another object of the present invention is to provide a casing shoe while, of substantially integral construction, is at the same 25 time made up of two rigidly united sections, one of which only is specially machined, while the other may be made of stock tubing of suitable inside and outside diameters.

30 An embodiment of the invention is described in the following specification and illustrated in the accompanying drawings, in which—

Fig. 1 is a central longitudinal section of 35 the upper and lower pieces of the shoe before joining.

Fig. 2 is a central longitudinal section of the two pieces united.

Ordinarily, a casing shoe consists of one 40 integral piece of high grade material, the outer surface of which is cylindrical and of uniform diameter from end to end and is turned true. The upper portion of the shoe is bored to produce a cylindrical interior 45 bore just below which is provided a tapered threaded zone to be screwed on to the casing end and below this threaded portion the shoe is further bored but the diameter of the bore is considerably less than the upper end 50 in which the casing fits, in order to secure a substantial leading end for the shoe.

By my invention I construct a shoe of which the upper end 2 is of stock tubular

material and which may, if necessary, be turned to the desired internal and outside 55 diameters and this section is beveled off at 2' on one end.

The lower section of the shoe is made of material of a higher degree of hardness and better quality than the upper section 2 and, 60 as shown, consists of a thick body part 3 of tubular form, the lowermost end of which is beveled to form an entering edge 4. The upper end of the shoe section 3 is internally threaded as at 5 to receive the casing end 65 and it is also beveled off as at 6 to coincide with the beveled edge 2' of the upper section, the sharp edges of the beveled portions registering and forming, when set in abutment, a V shaped groove which is to be filled with 70 a brazing or welding material indicated at 8 Fig. 2.

From the above it will be seen that I am enabled to utilize a lower grade stock material for the top section 2 and to utilize a 75 high grade entering section 3, the latter only of which requires internal machining to form its bore and to produce the threads. These sections are adapted to be rigidly joined as, preferably, by welding as is indicated by the welded joint 8.

Various modifications and changes may be resorted to within the spirit of the invention as claimed.

What is claimed is:

1. A well casing shoe comprising a cylindrical upper section having a cylindrical bore and a beveled edge on one end, and a lower shoe section of higher grade material and which is internally machined and having its upper end beveled; the beveled ends of the sections being abutted and a welded joint connecting the sections.

2. A well casing shoe construction comprising a lower shoe section of thick high grade material internally machined and having a casing thread in its upper end and an outwardly and downwardly bevel end face above the thread, and a cylindrical upper section of common thin material having a bevel lower end to match the bevel upper end of the first section, the two sections being welded together at their bevel ends.

In testimony whereof I have signed my name to this specification.

L. F. BAASH.
